UNITED STATES PATENT OFFICE.

MAX FRANZ HAHN, OF CHARLOTTENBURG, GERMANY.

TOBACCO-PIPE.

SPECIFICATION forming part of Letters Patent No. 727,789, dated May 12, 1903.

Application filed October 7, 1901. Serial No. 77,843. (No model.)

To all whom it may concern:

Be it known that I, MAX FRANZ HAHN, railway contractor, a subject of the German Emperor, residing in the city of Charlottenburg, in the Kingdom of Prussia, German Empire, (post-office address at 4 Wielandstrasse, Charlottenburg, care of Eugen Folkmar,) have invented a certain new and useful Tobacco - Pipe, of which the following is a specification.

This invention has reference to improvements in tobacco-pipes, and it provides means whereby the burning portion of the tobacco is always left exposed and open to the access of the air.

When compared with the tobacco-pipes now in use, my invention presents a number of important advantages, of which I may mention the following: The unused tobacco, unless it has already undergone the action of dry distillation, is always kept pure and fresh, as any transmission of the heat of combustion to this part of the tobacco is avoided. Thus it is obvious that even if the pipe should go out several times this will do no harm to the flavor of the tobacco, which will be the same as in freshly-charged pipes after the pipe is lighted again. Furthermore, the pipe as constructed according to my invention will retain the fire as long as an ordinary cigar, inasmuch as the zone of combustion is outside the pipe. Thus my invention does away with the tedious continuous sucking at the mouthpiece of the pipe which heretofore was a necessity when lighting the same. Besides, the improved tobacco-pipe presents the advantage of an automatic and exact regulation of the feed of the tobacco to the zone of combustion proportionate to the formation of ashes.

My invention is shown in a preferred form of construction on the accompanying drawings.

Figure 1 is a vertical section, Fig. 2 showing a modification, in vertical section also.

The body of the pipe consists of a tube *a*, preferably cylindrical, which serves for the reception and for protecting and feeding the plug of smoking-tobacco *b*. The tube *a* is open at the top, while at the bottom it is closed by a cap *m*, which may be attached by bayonet-joint or in any other suitable manner. A washer

p is inserted between the cap and the tube *a* for tightening purposes. The upper open end of the tube *a* is covered by the vaulted cap or burner-head *f*, which is provided with a conically-shaped opening *h* for the passage of the smoking-tobacco plug. For brevity's sake I will call this opening in the following specification the "burner-cone" wherever this opening is referred to.

i is the cover proper, which is detachably connected to the burner-head or top piece *f* and which closes the top opening of the pipe, while it also serves at the same time for the collection of the ashes. To the tube *a* the lateral tubing *d* is attached, which communicates by a suitable opening with the tube *a* and serves for the escape of the smoke and which is deepened at *e* to provide a chamber or sink for the accumulation of moisture or liquid particles in general.

g is a gasket for tightening the joint around the upper part of the tube *a*. Between the top part of the tube *a* and the lower rim of the burner-cone is a space *l*, which in the following specification will be referred to as the "burner-slot." This opening or burner-slot *l* is intended, first, to allow the escape of the smoke into the smoke-chamber *c*, the gases flowing in the direction indicated by arrows in the accompanying drawings. Then, second, the burner-slot allows a regulation of the progress of combustion, inasmuch as by adjusting the height of the said slot it is possible to accurately determine how large a quantity of the tobacco contained in the plug is to be subjected, first, to the combined action of heat and moisture, whereby it becomes softened and assumes a plastic condition suitable for feeding it into the burner-cone by the pressure of the spiral spring supporting the tobacco, and, finally, for introducing the thus-prepared tobacco into the zone of combustion. This softening action will increase the nearer the tobacco gets to the zone of combustion and the more perfect will be the plastic state it is to assume. As long as the plug of smoking-tobacco is still in a hard condition the said spring cannot act to force some of the tobacco through the burner-cone, inasmuch as the diameter of the hard plug is larger than the opening of the burner-cone.

After the pipe is lighted the part of the plug

immediately in front of the burner-slot soon becomes plastic, while the remainder of the plug remains hard and solid, as it is protected by the tube *a*. The plastic portion, however, 5 is immediately forced through the burner-cone and into the zone of combustion. Third, in case of particles of tobacco being rubbed off from the plug during its feeding forward the burner-slot will cause them to drop to the 10 side, so as not to interfere with the draft of the pipe. Fourth, then the burner-slot prevents the transmission of the heat of combustion upon the tube *a*.

The burner-slot and burner-cone herein referred to are proportionate to the extent of the zone of combustion. This is caused by the bottom part of the zone of combustion being always outside of the tube of the pipe, the relation being the same as in the case of 15 the bottom part of the flame in kerosene-burners. The burner-slot operates to induce the softening of a certain amount of tobacco. If the height of the burner-slot were excessive, too large a quantity of tobacco would 20 become softened, the burner-cone would fail to distribute the excess of soft tobacco thus produced, and it would not pass into the combustion zone. The tobacco would then also be forced to some extent into the cavity of 25 the smoke-chamber *c*, immediately adjoining the burner-slot. In this case the pipe would refuse to work, as it would become choked up. Then, on the other hand, if the lower 30 part of the zone of combustion is situated too high above the upper edge of the burner-cone while the quantity of plastic tobacco is in condition to pass through the opening of the burner-cone the pipe will also refuse to work, because the air which is sucked in does 35 not enter the zone of combustion. It is obvious, therefore, that the shape of the burner-slot is essential for the position of the zone of combustion and for the normal operation of the pipe, and it is evident that if the size 40 of the burner-slot is not bearing the proper relation to the burner zone, or, inversely, the zone of combustion will be displaced and imperfect or irregular combustion and waste of tobacco will ensue.

45 The shape of the burner-cone *h* is governed by the following two requirements: First, the burner-cone has to segregate the entire amount of the softened tobacco, and then it has to deliver it to the combustion zone; second, the dimensions of the burner-cone must be such that the quantity of tobacco fed from below into the burner-cone will operate to keep the lower end of the zone of combustion constant and above the upper rim of the 50 burner-cone, just as the flame of a kerosene-burner is kept above the upper rim of the burner—that is to say, the zone of combustion is situated entirely in the open air, so to speak, and not at the inside of the pipe.

55 The following advantages are obtained by this arrangement: (a) The pipe will keep the fire as long as an ordinary cigar and without

the necessity of the smoker sucking constantly at the mouthpiece of the pipe to keep it burning; (b) by this arrangement all the 70 fine flavor and taste of a superior grade of tobacco are retained; (c) furthermore, I am enabled to use in my improved pipe any kind of cigar-tobacco, which heretofore could not be utilized in pipes. All these kinds of tobacco 75 may be smoked in a pipe constructed according to my invention and will afford great enjoyment and yield a fine flavor to the smoker.

The device described operates as follows: 80 In order to fill the pipe, the cap *m* is detached and the spring *k*, which is preferably attached to the cap *m*, is pulled out. Then the plug of smoking-tobacco is introduced from below into the tube *a*, and after the reinsertion of 85 the spring *k* and the closing of the cap *m* the plug is forced against the burner-cone *h*. (Compare also Fig. 2 of the drawings.) The pipe is then ready for use and is lighted at 90 the top.

In Fig. 1 the plug of tobacco is shown partly burned up already. Part *n* of the plug is already converted into ashes while part *o* is still burning. *q* is the softened plastic part of the plug which has become segregated in 95 the burner-cone. Fig. 2 shows the plug of tobacco intact and in position ready for immediate lighting. As soon as the heat radiating from the incandescent zone *o* and the moist vapors contained in the smoke have 100 reached the upper part of the tobacco-plug they act to soften the same, and after this part has become plastic the spring *k* forces the softened tobacco through the burner-cone and into the zone of combustion. The feed 105 of the tobacco becomes very regular and in proportion as tobacco is consumed in smoking. If the smoking is discontinued, the pipe will go out within a few minutes. It appears from this that the smoker enjoys all the pleasure and flavor of a freshly-filled pipe until 110 the said plug is perfectly used up, inasmuch as the gases of combustion, as shown in the drawings, do not penetrate through the unburned portion; but they are carried off lat- 115 erally and around the pipe.

Fig. 2 shows a suction smoking-pipe embodying my invention; but it is obvious that the invention may be applied to other styles of pipes as well.

What I claim, and desire to secure by Letters Patent of the United States, is—

1. In a smoking tobacco-pipe the combination with a double-walled bowl and means in the lower part of said bowl for automatically 125 feeding the tobacco, of an upwardly-tapering head attached to the outer walls of said bowl, an end opening in said head of smaller diameter than the inner diameter of the bowl, an annular passage between the rim of the inner 130 walls of the bowl and the base of the inwardly-tapering head and a lateral educt-pipe in connection with said passage.

2. In a smoking tobacco-pipe in combina-

tion with a bowl and a lateral educt-pipe, an inner casing or receptacle integral with said bowl and of smaller diameter and reaching below the bottom of said bowl, a conical upwardly-tapering open top attached to the rim of said bowl above and at a distance from the rim of said receptacle or inner casing and an annular passage between the bowl and the inner casing and of substantially the height

of the said bowl and a spring at the bottom of said receptacle to support and feed the tobacco.

In witness whereof I have hereunto set my hand in presence of two witnesses.

MAX FRANZ HAHN.
